Frank S. Ober
Haldor M. Chapman

Fig. 2.

The diagram illustrates a double-walled tube. The outer wall is represented by a thick black line, and the inner wall by a thin black line. A horizontal dashed line, representing the longitudinal axis, passes through the center of the tube. The tube is divided into several sections by vertical lines. On the left side, there are two vertical lines, with a series of small circles (representing pores) between them. On the right side, there are three vertical lines, with a series of small circles between the first and second lines, and a series of larger circles between the second and third lines. The labels are as follows:

- A:** A label placed above the first series of small circles on the left.
- B:** A label placed below the second series of small circles on the right.
- C:** A label placed below the first series of small circles on the right.
- D:** A label placed above the second series of small circles on the right.
- E:** A label placed above the third series of small circles on the right.
- SPA:** A label placed to the right of the third series of small circles on the right.
- SPA:** A label placed to the right of the second series of small circles on the right.
- SPA:** A label placed to the right of the first series of small circles on the right.

UNITED STATES PATENT OFFICE.

CHARLES G. BURKE, OF NEW YORK, N. Y.

WIRELESS TELEGRAPHY.

SPECIFICATION forming part of Letters Patent No. 737,072, dated August 25, 1903.

Application filed September 21, 1901. Serial No. 76,059. (No model.)

To all whom it may concern:

Be it known that I, CHARLES G. BURKE, a citizen of the United States, residing at the city of New York, in the borough of Brooklyn and State of New York, have invented certain new and useful Improvements in Wireless Telegraphy, of which the following is a full, clear, and exact description.

In wireless telegraphy it is usual to employ the Morse code for the transmission and recording of messages. The signals in this code are composed of dots and dashes, and these dots and dashes are produced in wireless telegraphy by the impulses sent into space from a sending-station acting through a coherer in the receiving-station, which controls a local battery and local recorder. Inasmuch as the impulses sent into space in wireless telegraphy are necessarily uniform in their duration and that two or more of such impulses are needed to complete each dash and that the circuit continuity of the coherer has to be interrupted at the end of each impulse it has not heretofore been possible in wireless telegraphy to produce dashes with the same facility and accuracy as it has been to produce dots. The tapping of the coherer after each impulse mutilates the dashes to such an extent that the deciphering of the record becomes more or less guesswork even to skilled operators.

The purpose of this invention is to enable Morse dashes to be produced in wireless telegraphy as readily and as accurately as Morse dots, and thereby to insure as perfect signals as those made over an ordinary land-line.

In carrying out my improvement I preferably employ what is known as the "Continental Morse Code," the same which is now in use on all submarine cables and on European land-lines. In recording signals I cause the impulses to interrupt the continuity of an inked line normally being made by the recorder. Each interruption is of the same length, and that portion of the line traced between the interruptions is either a dot or a dash, depending on the interval between the interruptions. An interval greater than that required to record a dash indicates the space between letters and is recorded as a long line. The adaptability of this method

of transmission to wireless telegraphy, where the current impulses are necessarily of the same duration, is at once apparent.

My invention will be described with reference to the accompanying drawings, in which—

Figure 1 is a diagram of the circuits and apparatus of a transmitting and receiving station equipped according to my invention. Fig. 2 illustrates sections of the sending and receiving tapes with characters indicated thereon.

Referring to the drawings by letter, A represents a transmitting-station and B a receiving-station for wireless telegraphy. At the station A is located the usual Ruhmkorff coil *a* or other source of high-tension electricity. This coil has the usual appliances for producing the oscillations, which appliances may be of any of the well-known forms employed in wireless telegraphy. In the primary circuit 1 of the coil *a* are the usual battery *a'* and the circuit-controller *a''*, the latter, as illustrated, being operated to close the circuit by an electromagnet *b* in a circuit 2, containing battery *b'* and circuit-controller *b''*. The latter device has a stylus *b''*, adapted to drag upon the surface of a perforated tape *t*, which is supported by a wheel *t'*. When a perforation in the tape is presented to the stylus, the stylus drops into it and closes the circuit 2, thus energizing magnet *b*, which in turn closes the circuit 1. The stylus is immediately raised by the further movement of the tape, and circuit 2 is broken, which results also in the breaking of circuit 1. This sends an impulse in the usual manner from the transmitting-electrode *T* through space to the receiving-electrode *T'*.

At the receiving-station B is located the usual coherer *c*, which is supposed to be fitted with its tapping and other appliances. The coherer controls the local circuit 3, including battery *c'* and electromagnet *c''*. The latter acts as a relay to close the recording-circuit 4, which contains battery *d* and the recorder-magnet *e*.

p is a receiving-tape on which the signals are recorded. This tape passes over a wheel *p'*, supported by the armature-lever *e'* of magnet *e*. The tape is normally held against the

point of a pen or siphon s , so that while the magnet e is deenergized a continuous line will be traced on the tape.

The perforations of the sending-tape t are all of the same size; but they are spaced apart variously to indicate dots, dashes, and spaces between letters and words, the shortest space being a dot, the next longer being a dash, the next longer a space between letters, and the longest (when used) being a space between words. Whenever a space between perforations is presented to the stylus b^3 , the pen s is against the tape p , as will now appear from the description of the operation.

Under normal conditions when no current is on any of the circuits a continuous line is being traced by the pen upon the tape p . When a perforation is presented to the stylus b^3 , the latter closes the circuit 2 and energizes magnet b . This closes circuit 1 and allows a current to flow through the primary of the induction-coil a . Immediately thereafter the circuit is broken by the stylus passing out of the perforation, and on the opening of the circuit 1 which follows an impulse of the Hertzian waves is sent out through space from the terminal T . This impulse reaches the receiving-terminal T' and affects the coherer c , which energizes the circuit 3 and its magnet c^2 . This closes the recorder-circuit 4, causing the armature-lever e' to drop the wheel p , so that the tape is removed from the point of the pen s . As this impulse is only momentary, the tape p is immediately returned to the pen s , a brief interruption having been made in the traced line to indicate the beginning of a dot. If the next perforation in the tape t is the space of a dot from the previous perforation, the circuits described will again be closed immediately, which will cause another interruption in the line on the receiving-tape, the short line between the two spaces defining a dot. If the next perforation in the tape t had been separated from the first by a dash-space, the interruptions of the line on the receiving-tape would have been correspondingly more removed and would have indicated between them a dash. In like manner the larger

spaces necessary for transmission can be sent 50 and received.

It is evident that an ordinary key can be substituted for the circuit-controller a^2 and the circuit 2; but owing to the difficulty of accurately determining the intervals of "no current" with a hand-key the automatic tape is preferable.

It will thus be seen that by applying to wireless-telegraph systems the herein-described means for recording dots and dashes 60 by the mere separation of the impulses the difficulties heretofore encountered in deciphering the message is overcome.

Having described my invention, I claim—

1. In a system of wireless telegraphy, a 65 transmitting-station provided with means for sending uniform operative impulses or group of impulses into space at variable intervals, in combination with a receiving-station provided with apparatus responsive to such impulses, a recorder normally tracing a continuous line and means whereby the line is interrupted by each impulse, whereby that portion of the line between the interruptions will indicate the signals. 75

2. In a system of wireless telegraphy, a sending-station provided with the usual device, such as a Ruhmkorff coil for creating Hertzian waves, a circuit-controller in the primary circuit of said device, a moving perforated tape whose perforations are of uniform length and whose spaces between the perforations define the signals, and means whereby all perforations will cause uniform changes in the said primary circuit, in combination with a receiving-station provided with the usual imperfect contact-receiver and its local circuit, a moving tape, a line-tracer normally tracing a continuous line on said tape and means whereby each response 80 of the coherer will cause an interruption of the traced line. 85

In witness whereof I subscribe my signature in presence of two witnesses.

CHARLES G. BURKE.
